EXERCISER

William L. King, Springfield, Oreg., assignor to Nathan E. Knecht, Springfield, Oreg.

Filed Mar. 9, 1970, Ser. No. 21,818

Term of patent 14 years

Int. Cl. D21—02

U.S. Cl. D34—5

FIG. 1 is a perspective view of the exerciser, showing my new design;

FIG. 2 is a top plan view of the article;

FIG. 3 is a bottom plan view of one side of the article (the opposite side being identical in appearance); and

FIG. 4 is a side elevation of the article.

I claim:

The ornamental design for exerciser, as shown and described.
